UNITED STATES PATENT OFFICE.

DAVID M. ROSS, OF YOUNGSTOWN, FLORIDA.

DISPENSING-CABINET.

1,229,525.

Specification of Letters Patent. Patented June 12, 1917.

Application filed December 1, 1916. Serial No. 134,376.

To all whom it may concern:

Be it known that I, DAVID M. ROSS, a citizen of the United States, residing at Youngstown, in the county of Bay and State of Florida, have invented a new and useful Dispensing-Cabinet, of which the following is a specification.

The present invention appertains to dispensing appliances, and is particularly an improvement over the dispensing cabinet disclosed in my Patent No. 1,160,448 granted November 16, 1915.

It is the object of the invention to provide a display stand and dispensing cabinet for a variety of materials, such as coffee, beans, peas, rice, etc., the device being constructed to hold various materials which can be dispensed through a common funnel or chute into a bag, sack or other receptacle.

A further object of the invention is to provide a dispensing cabinet having a novel and improved bin construction for holding the various materials and directing them in separate streams to the valves, and to provide for a compact construction which can form a fixture in the store.

Another object of the invention is to provide the device with novel controlling valves operable to establish and cut off the flow of the various materials.

The invention also has for its object the provision of a dispensing cabinet of the nature above indicated which is comparatively simple, compact and inexpensive in construction, which is improved generally in its construction and details, and which is practical, serviceable and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a front view of the cabinet, 50 portions being broken away.

Fig. 2 is an enlarged bottom plan view illustrating the controlling valves.

Fig. 3 is a sectional detail taken on the line 3-3 of Fig. 1.

Fig. 4 is a top plan view of the cabinet with one of the doors of the bins swung open.

Fig. 5 is a vertical section taken on the line 5-5 of Fig. 4.

In carrying out the invention, there is provided a casing 1 preferably of elliptical contour, and as a practical and convenient way of supporting the casing 1 upon a counter or other support within a store or elsewhere, there is provided a stand including the upper elliptical frame 2 in which the casing 1 is fitted, said casing having lugs 3 seatable upon the frame 2 from which the casing can be lifted. The frame 2 is supported by the legs 4 having their upper ends attached to said frame, and braces 5 connect the legs and frame to render the structure rigid.

The casing 1 is provided with a hopper 75 bottom 6 whose lower portion is elongated and provided with a longitudinal series of outlet openings 7. The casing 1 is provided with a longitudinal partition 8 therein and a transverse partition 9, dividing the casing into four bins for holding four different materials, although any suitable number of bins can be provided. The partitions extend within the hopper bottom 6, and the partition 9 separates two bins between the intermediate openings 7. The lower portion of the longitudinal partition 8 is provided with oppositely offset portions 10 extending partially around the openings 7, as seen in Fig. 3, whereby one bin at each side of the partition 9 will communicate with one of the two respective openings 7, while the other bin at the same side of the partition will communicate with the other opening. Thus,

by the provision of the partition 9 which divides the openings 7 in pairs, and the provision of the offset portions 10 in the longitudinal partition 8, the bins communicate 5 with the respective openings 7.

In order to close the bins to exclude dust and dirt therefrom, semi-elliptical doors 11 are hinged, as at 12, to the upper edge of the longitudinal partition 8 and swing over 10 and close the bins at the opposite sides of the longitudinal partition. These doors can be readily swung open for filling these bins from time to time.

In order to display the materials, a depending elongated spout 14 for the hopper bottom 6 is provided at its upper edge with an outstanding flange 17 bolted or otherwise fastened to the outstanding flange 13 with which the lower portion of the hopper bottom 6 is provided. The spout 14 is provided with partitions 15 therein dividing the spout into chutes or passages 16 into which the materials flow. The front sides of the passages or chambers 16 are provided with 25 glass or transparent windows 18 in order that the customers can observe their contents, thus providing for the display of the materials.

In order to control the discharge of the materials from the passages 16, a horizontal plate 19 is secured to the lower edge of the spout 14 and has a depending marginal flange or apron 20. A funnel 21 is hinged, as at 22, to one end of the apron 20, and the mouth of the funnel is swingable upwardly into the apron 20 to receive any of the materials discharged from the passages 16. A catch 23 is carried by the funnel opposite to the hinge 22 to be shaped into engagement with the apron 20 for holding the funnel in place. An extension sleeve 24 is slideable upon the spout 25 of the funnel, the free end of the spout having a leaf spring 26 bearing against the sleeve 24 to hold it in any position to which it is slid. When the sleeve 24 is raised, a bag or other receptacle can be placed under the funnel, and the sleeve 24 then slid downwardly into the receptacle to direct the material into the receptacle without spilling. After the receptacle is filled, the sleeve 24 can be raised to permit the receptacle to be removed without interference. The frame 2 carries a catch 27 engageable with the sleeve 24 and spout 25 for holding 50 the hopper out of the way when it is swung to one side and upwardly, as seen in dotted lines in Fig. 1.

The plate 19 has openings 30 communicating with the lower ends of the passages 16, and rectangular valve frames or slides 28 are slideable through the rear wall of the apron 20 to be operated by the clerk or salesman. The inner end portions of the

frames 28 are provided with webs 29 providing valves for closing the openings 30. 65 Rearwardly projecting stems 31 are carried by the front wall of the apron 20 and the forward ends of the frames 28 are slideable upon said stems, coiled wire expansion springs 32 surrounding the stems and being 70 confined between the forward wall of the apron 20 and forward ends of the frames 28 whereby to normally slide the valves rearwardly to close the openings 30.

When the hopper 21 is swung into position below the valves, a selected valve can be pushed forwardly to open position from the rear of the cabinet, in order to dispense the desired material through the funnel into the receptacle, the valve being closed as soon as released. This provides a convenient and serviceable manner of dispensing the materials contained in the bins. The funnel 21 can be swung out of the way for purpose of cleaning or exposing the valves and interior 85 of the funnel.

Having thus described the invention, what is claimed as new is:

1. A dispensing cabinet embodying a stand having legs and an upper frame, a 90 casing fitted within said frame and having portions seating thereon, the hopper bottom having a lower series of discharge openings, the casing having a plurality of bins communicating with said openings, a depending 95 spout attached to said hopper bottom and having passages communicating with said openings, said spout having windows for said passages to expose the material therein, valves for controlling the discharge of the 100 materials from said passages, and means suspended from said spout for directing the material from all of said passages to a receptacle therebelow.

2. A dispensing cabinet embodying a cas- 105 ing having a hopper bottom provided with a longitudinal series of discharge openings, the casing having a plurality of bins communicating with said openings, an elongated spout depending from the hopper bot- 110 tom and having vertical passages communicating with said openings and windows exposing the materials within said passages, valves for controlling the discharge of the material from the lower ends of said pas- 115 sages, and means for catching the material from all said passages and directing it into a receptacle.

3. A dispensing cabinet embodying a horizontal plate having a series of openings and 120 a depending marginal apron, a plurality of bins having means for conducting material to said openings, a funnel adapted to fit said apron, rectangular frames slideable through one wall of said apron below said 125 plate and having webs at their inner end

portions providing valves for said openings, and spring means for moving said valves under said openings.

4. A dispensing cabinet embodying a horizontal plate having a series of openings and a depending marginal apron, a plurality of bins having means for conducting material to said openings, a funnel adapted to fit said apron, rectangular frames slidable 10 through one wall of said apron and having webs at their inner end portions providing valves for said openings, stems carried by the opposite wall of said apron slidably en-

gaging the inner ends of said frames, and coiled wire expansion springs upon said stems confined between the last mentioned wall of the apron and the inner ends of the frames, to move the valves under said openings.

In testimony that I claim the foregoing 20 as my own, I have hereto affixed my signature in the presence of two witnesses.

DAVID M. ROSS.
